US00D930774S

(12) **United States Design Patent** (10) **Patent No.:** **US D930,774 S**
 (45) **Date of Patent:** **** Sep. 14, 2021**

(54) **GOLF CLUB HEAD**
 (71) Applicant: **PARSONS XTREME GOLF, LLC**,
 Scottsdale, AZ (US)
 (72) Inventors: **Michael R. Nicolette**, Scottsdale, AZ
 (US); **Bradley D. Schweigert**, Cave
 Creek, AZ (US)
 (73) Assignee: **PARSONS XTREME GOLF, LLC**,
 Scottsdale, AZ (US)
 (***) Term: **15 Years**
 (21) Appl. No.: **29/723,430**
 (22) Filed: **Feb. 6, 2020**

Related U.S. Application Data

(63) Continuation-in-part of application No. 29/717,438, filed on Dec. 17, 2019, now abandoned, and a continuation-in-part of application No. 29/716,166, filed on Dec. 6, 2019, now abandoned, and a continuation-in-part of application No. 29/709,349, filed on Oct. 14, 2019, and a continuation-in-part of application No. 29/703,103, filed on Aug. 23, 2019, now Pat. No. Des. 921,787, and a continuation-in-part of application No. 29/698,109, filed on Jul. 15, 2019, now abandoned.
